United States Patent

Des. 241,239

Patented Aug. 31, 1976

241,239

BOAT

Howard G. Goldsmith, Cranston, R.I., assignor to
Todd Enterprises, Inc.

Filed Nov. 24, 1975, Ser. No. 634,477

Term of patent 14 years

Int. Cl. D12—06

U.S. Cl. D12—62

FIG. 1

FIG. 2

FIG. 3

FIG. 4

FIG. 5

FIG. 6

FIG. 1 is a perspective view of a boat showing my new design;

FIG. 2 is a bottom plan view thereof;

FIG. 3 is a top plan view thereof;

FIG. 4 is a rear elevational view thereof;

FIG. 5 is a front elevational view thereof; and

FIG. 6 is a side elevational view thereof.

I claim:

The ornamental design for a boat, substantially as shown.
